US0D1098639S

(12) **United States Design Patent** (10) **Patent No.:** **US D1,098,639 S**
(45) **Date of Patent:** **** Oct. 14, 2025**

(54) **MULTIFUNCTIONAL VACUUM CLEANER**

(71) Applicant: **Taiyuan Jietong Cross-border E-commerce Co., Ltd.**, Shanxi (CN)

(72) Inventor: **Jie Wang**, Shanxi (CN)

(73) Assignee: **Taiyuan Jietong Cross-border E-commerce**, Taiyuan (CN)

(**) Term: **15 Years**

(21) Appl. No.: **29/993,570**

(22) Filed: **Mar. 14, 2025**

(30) **Foreign Application Priority Data**

Mar. 6, 2025 (CN) 202530102257.7

(51) **LOC (15) Cl.** **15-05**

(52) **U.S. Cl.**

USPC **D32/18**

(58) **Field of Classification Search**

USPC D15/199; D21/526, 578; D32/15, 17, D32/18, 21

CPC A47L 5/00; A47L 5/12; A47L 5/22; A47L 5/24; A47L 7/00; A47L 7/0076; A47L 11/00; A47L 11/24; A47L 11/32; A47L 11/33

(57) **CLAIM**

The ornamental design for a multifunctional vacuum cleaner, as shown and described.

DESCRIPTION

FIG. 1 is a first perspective view of a multifunctional vacuum cleaner showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is an enlarged view of portion of FIG. 2.

The broken lines in the drawings depict portions of the multifunctional vacuum cleaner that form no part of the claimed design.

The dash-dot lines illustrate the boundary of the enlarged views and form no part of the claimed design.

1 Claim, 9 Drawing Sheets
